11 Claims. (Cl. 9—400)

ABSTRACT OF THE DISCLOSURE

Disclosed herein is a segmented float for floating a diving apparatus comprising a combined engine and air compressor unit. The segmented float comprises the assembly of a plurality of spaced buoyant segments which can be formed from an expanded plastic, such as polystyrene or other buoyant material, and which, together, are intended to surround the engine-compressor unit and to provide the necessary buoyancy to float the entire unit. The float segments are secured to the engine-compressor unit by a rubber band or belt seated in a circumferential groove in the segments. The cross section of the segments is larger below the water line than above. The upper contour of the segments is sloping to facilitate draping of the air hoses used in such an apparatus.

Cross reference to related application

The float of the present invention is a further development of the subject matter disclosed in co-pending United States application Ser. No. 516,857 filed by Ronald R. Quiram and Gaylord M. Borst.

Summary of invention

In accordance with the invention there is provided a 35 segmented float adapted for floating a device, such as, for example, a combined engine-compressor apparatus which is usable by skin divers and which is intended for flotation on the surface of the water above or near the divers. Heretofore, an inflatable annular tube has been used to 40 float such devices. However, such tubes are subject to puncture and leakage which can endanger the divers and result in sinking and consequent loss of the engine and compressor. The segmented float of the invention avoids such problems by utilizing a buoyant material such as an 45 expanded plastic having a large number of small air cells. The use of a number of segments permits compact storage of the individual float segments in a stacked manner in a zipper bag or the like. When installed on an engine-compressor, the float segments are spaced to provide gaps 50 for discharge of engine fumes which could otherwise accumulate beneath the floatation ring and above the water surface.

Kinking of air supply hoses near the engine-compressor is minimized by a sloping upper surface on the float 55 segments.

Further objects and advantages of the present invention will become apparent by reference to the following description and accompanying drawings.

FIGURE 1 is a perspective view of a float which embodies various of the features of the invention and which is shown in supporting relation to an engine-compressor unit.

FIGURE 2 is an enlarged fragmentary plan view of the segmented float of FIGURE 1.

FIGURE 3 is a fragmentary sectional view taken along line 3—3 of FIGURE 2.

FIGURE 4 is an enlarged perspective view of a spacer and clamp shown in FIGURE 2.

Detailed description

Referring now to the drawings, there is illustrated in FIGURE 1 an engine-compressor unit which is generally designated 10 and which is intended for use as an air source for underwater diving. The construction of the engine-compressor unit can be as described in co-pending application Ser. No. 516,857. The invention encompasses a float 12 consisting of an assembly of segments, each segment constituting a fractional portion of the whole, with each segment constructed of a buoyant material. Various buoyant materials can be used such as balsa wood, micro-balloon or polyurethane. In the disclosed construction, an expanded plastic, such as polystyrene foam having a large number of buoyant cells is utilized. Various float configurations are within the purview of the invention, the choice of the particular configuration being largely dictated by the configuration of the associated device which is to be supported by the float and the arrangement for securing the float to the unit.

In the disclosed construction the float 12 comprises an assembly of three individual segments 14 with each segment constituting a fractional part of an annulus or toroid. A horizontal plane through a segment 14 generally comprises a sector of a circle. When in use the segments are circumferentially arranged around the engine-compressor unit 10 to form the generally toroidal or annularly shaped float 12. More than three individual segments and other shapes could be utilized to obtain various of the advantages and features of the invention. With the use of two segments some of the advantages and features of the invention can be obtained but compact storage of the units in stacked relation in a bag becomes less advantageous because of the length of each segment.

In accordance with the invention means are provided for securing the float segments 14 in a toroidal assembly around the engine-compressor unit 10. Various means can be utilized including means affording pre-assembly of the segments, with the assembly then being secured to the engine-compressor unit 10. In the disclosed construction, the means provided includes upper and lower arcuate recesses 16 and 18 which provide seats for the mounting rings respectively 20 and 22 of the engine-compressor unit 10. Secure engagement of the float segments 14 to the mounting rings 20 and 22 is afforded by a tongue 23 which is formed between the recesses 16 and 18 and which projects between rings 20 and 22 when the segments 14 are assembled.

To provide gaps 40 for discharge of engine fumes, the floats when assembled are separated by spacers 34 carried on one or both rings 20. The spacers also prevent circumferential movement of the segments around the mounting rings 20 and 22. The spacers 34 have an axial slot 35 and are preferably flexible to facilitate installation on the rings, and also include an annular groove 36 which receives a clamp 38.

To provide a bias maintaining the segments 14 in secure engagement in their intended position, the spacers 34 are slightly compressed when the segments 14 are arranged around the engine-compressor unit 10. Soft feet for supporting the unit on a deck or pier are afforded by the spacers 34 which are mounted on the lower ring 22 and which extend slightly beneath the bottom 42 of the float segments 14.

In the modified embodiment disclosed in FIGURE 5, the gaps for escape of engine fumes between the segments 14 are provided by integral circumferential extensions 43 at one end of each float rather than with spacers.

Also included in the means to secure the floats in an assembly around the engine and compressor unit 10 is a belt or band 44 which rides in a peripheral groove 46 and which circumscribes the float 12. The belt 44 can be a

large rubber band or a belt with adjustable connecting means at the ends.

To minimize kinking of the air supply hoses when a diver is beneath the engine-compressor unit 10, the float segments are provided with an arcuate sloping upper face 50, thereby providing a rest for the air supply hoses 51. The float segments 14 have a slightly larger cross section in the lower portion 52 for increased buoyancy to keep the engine-compressor unit 10 riding above the water surface.

The individual float segments 14 may be left permanently installed on the engine-compressor unit 10 or they may be stored in a bag or carrying case in stacked relation and installed when the engine-compressor 10 is used.

Various of the features of the present invention are disclosed in the following claims.

What is claimed is:

1. Apparatus comprising an assembly of a compressor and an engine connected to said compressor for driving said compressor, a float comprising a plurality of segments of expanded plastic surrounding said assembly, and means for releasably assembling and reassembling said segments in circumferentially spaced relation to each other around said assembly to support said assembly on a fluid surface.

2. Apparatus in accordance with claim 1 wherein said means for releasably assembling said segments to said assembly includes a peripheral groove in each of said segments and a band in said groove circumscribing said segments.

3. Apparatus comprising the assembly of an air compressor and an engine connected to said air compressor for driving said compressor, a pair of spaced members on said assembly, a float constructed of expanded plastic and including an extending tongue portion, and means for securing said float to said members with said tongue portion therebetween to support said assembly on a fluid surface.

4. Apparatus comprising the assembly of an air compressor and an engine connected to said air compressor for driving said compressor, a pair of spaced members on said assembly, a float constructed of a plurality of segments of expanded plastic, each segment including an extending tongue portion, and means for securing said segments to said members with said tongue portions therebetween to support said assembly on a fluid surface.

5. Apparatus in accordance with claim 4 wherein said means for securing said segments to said members includes a peripheral groove in each of said segments and a band in said groove circumscribing said segments.

6. Apparatus comprising the assembly of an air compressor and an engine connected to said air compressor for driving said compressor, a pair of spaced members on said assembly, a float constructed of a plurality of segments of expanded plastic, each segment including an extending tongue portion, and means for securing said segments to said members in circumferentially spaced relation to each other and with said tongue portions therebetween to support said assembly on a fluid surface.

7. Apparatus in accordance with claim 6 wherein said means for securing said segments to said members includes a peripheral groove in each of said segments and a band in said groove circumscribing said segments.

8. Apparatus in accordance with claim 6 wherein said means for securing said segments in circumferentially spaced relation to each other includes circumferentially extending extensions on said segments.

9. Apparatus in accordance with claim 6 wherein said means for securing said segments in circumferentially spaced relation to each other comprises spacers carried on said members between said segments.

10. Apparatus in accordance with claim 7 wherein said band is releasably connected to said segments to maintain said segments in secured condition relative to said members.

11. Apparatus in accordance with claim 6 wherein said segments have a sloping upper surface.
